UNITED STATES PATENT OFFICE

WALTER D. BUTZ, OF NORRISTOWN, PENNSYLVANIA, ASSIGNOR OF ONE-HALF TO
LOUIS N. D. WILLIAMS, OF ELKINS PARK, PENNSYLVANIA

HOSIERY PRINTING APPARATUS

Application filed June 18, 1930. Serial No. 462,055.

This invention relates to apparatus useful in printing articles such as seamless stockings made from tubular material with lines intended to serve as guides incident to trimming and seaming for the purposes of better fitment of the stockings. More particularly, my invention has reference to printing apparatus useful in connection with the manufacture of hosiery such as described in U. S. Letters Patent #1,752,587 granted me under date of April 1, 1930.

The main object of my invention is to provide a printing apparatus for the above designated purpose, which is simple in construction, efficient in operation, adaptable to accurately line marking stockings of different sizes, and moreover capable of imprinting upon the stockings the proper size numbers and for ornamental design figures at the same time that the trimming and seaming guide marks are applied.

Still other objects and attendant advantages of this invention will be manifest from the detailed description following in connection with the attached drawings, wherein Fig. I is a plan view of my stocking printing apparatus with the parts in printing position.

Fig. II is a similar view of the apparatus but showing the stocking supporting form or board in position to facilitate withdrawal of the stocking therefrom after printing and its delivery to an associated sewing machine for cutting and seaming.

Fig. III is a staggered longitudinal sectional view of the apparatus taken as indicated by the arrows III-III in Fig. I.

Fig. IV is a cross section taken as indicated by the arrows IV-IV in Fig. I.

Fig. V is a cross section taken as indicated by the arrows V-V in Fig. II.

Fig. VI is a cross sectional view taken as indicated by the arrows VI-VI in Fig. I.

Fig. VII is a view similar to Fig. VI with the parts in different positions.

Fig. VIII is a fragmentary plan view of the heel portion of the stocking supporting board drawn to a larger scale.

Figs. IX and X are fragmentary detail sectional views taken as indicated by the arrows

IX-IX and X-X in Fig. II and likewise drawn to a larger scale.

As herein delineated, the hosiery printing apparatus of my invention comprises an appropriately profiled flat form or board 10 for supporting the stockings during marking, said board being swingable about a vertical pivotal mounting 11 toward and away from a printing mechanism 12 resting on a table 13 alongside of a sewing machine 14. This sewing machine may be of any approved commercial type such as used in the art for over-edge seaming, and equipped with a suitable fabric cutting attachment, not shown.

In the present instance, the pivotal mounting 11 for the hosiery board 10 has the form of a tubular post 15 with a foot flange 16 whereby it is rigidly secured to the floor at a point adjacent the table 13. As shown, the stocking board 10 is freely fulcrumed on the post 15 with its pivot boss resting on an actuating lever 17 adapted to be manipulated by the knee of the operator. This actuating lever 17 is likewise free on the post 15 and rests on a split clamp collar 18 which is rotatably adjustable on said post, and which has a projecting stop finger 19 to limit outward movement of the lever 17 under the influence of a torsion spring 20. Another coiled spring 21 with its opposite ends engaging the stocking board 10 and the actuating lever 17 serves as a flexible coupling means between these elements. The motion of the stocking board 10 is limited by stop fingers 22, 23 projecting from split clamp collars 24 which are individually adjustable rotatively about the upper end of the post 15.

To enable adaptation of the board 10 to stockings of different sizes, it is provided with a positionally adjustable heel piece 25 (Figs. II and VIII), whereof the exposed rounded part 26 is of the same thickness and therefore flush, top and bottom, with said board. A tongue 27 of reduced thickness on the heel piece 25 engages an edge groove 28 in the board 10, see Fig. IX. As shown in Figs. VIII and X, the tongue 27 has end extensions 29 which are pressed inwards by leaf springs 30 anchored at one end to filler or retainer pieces 31 that close portions of the edge groove 28. Medially of the

upper inner edge of its exposed rounded portion 26, the heel piece 25 has a lateral arrow-head projection 32 capable of being selectively registered with index notches 33 5 along the contiguous edge of the board 10, said notches being numbered in accordance with standard stocking sizes. With the described arrangement, the heel piece 25 may be slid along the hosiery board 10 to different 10 positions of adjustment as required wherein it will be yieldingly retained by action of the springs 30 and by cooperation between the arrow-head projection 32 with the edge notches 33 of the board 10.

15 The base 35 of the printing mechanism 12 is of hollow rectangular configuration, and, adjacent one of its longer sides, has upstanding bearing lugs 36 for a fulcrum rod 37 whereon is mounted, for up and down swinging movement, a frame 38. The upward movement of this frame 38 is yieldingly opposed by a spring 39 within the base 35 engaging an arm 40 secured to and depending from the fulcrum rod 37 at the center, see 20 Figs. I and IV, the pressure of said spring being adjustable by means of a screw 41 taking into the back wall of said base. Downward movement of the frame 38 is definitely limited by engagement of the depending 25 arm 40 with a stop screw 42 also adjustable in the back wall of the base 35. The side arms 43 of the frame 38 are integrally joined at the front of the printing device 12 by a longitudinally extending bar 44 whereto 30 is attached a type member consisting of two aligned sections 45, 46. These sections 45, 46 are both fashioned from sheet metal with downturned frontal edges 47 which, collectively considered, are substantially counterconformative with the rear edge of the lower leg and foot portions of the stocking form 10 and jointly constitute the type for printing a line mark, such as shown at L in Fig. 35 II on the upper face of the mounted stocking S, to serve as a guide line for the purpose of 40 subsequent sewing and cutting. That section 45 of the type member which corresponds to the toe of the stocking board 10 is fixedly attached to the bar 44 of the swinging frame 38 by screws 45a, while the companion section 46 is relatively adjustable lengthwise of the bar 44 to correspond with the adjustment of the heel piece 25 on the stocking board 10 in adapting the apparatus to marking stockings 45 of different sizes. Such adjustment of the type section 46 is made possible through slotting thereof as at 48 for passage of clamp securing screws 49 that take into the longitudinal bar 44 of the swinging frame 38. 50 Numbered graduations are placed along one edge of one of the slots 48, as shown in Figs. I and II, for coordination with an index pointer 50 associated with the corresponding clamp screw 49. In order to predetermine 55 continuity of the line L imprinted upon the

stocking S, the impress edges 47 of the two type sections 45, 46 are extended, as at 51 in Figs. I and II with formation of overlapping juncture tongues. The bar 44 of the swinging frame 38 also carries a disk 52 with 50 number type on its periphery which accord with the index numbers respectively on the adjustable heel piece 25, of the stocking board 10, and on the adjustable type section 46. As shown, the disk 52 occupies the heel bight 55 53 of the type section 46 and is secured on one end of an axis 54 having journal support in a bearing 55 upstanding from said type section. To the other end of the axis 54 is secured a gear pinion 56 which meshes with a rack 57 attached to the cross bar 44 of the swinging frame 38. By virtue of these provisions, it will be seen that as the type section 46 is moved from one position of adjustment to another, the type disk 52 is concurrently rotated and the proper type brought into position to print the size number on the stocking S at the same time that the line mark L is printed thereon. During each actuation of the apparatus in a manner presently explained, the impress edges 47 of the type sections 45, 46 take dye color or ink from a pad 60 recessed in the top of a carriage 61 which has capacity for sliding movement in a direction transversely of the base 35 of the printing mechanism 12. As shown in Fig. III, the under surface of the carriage 61 is recessed along its side edges as at 62 to engage upstanding machined guideways 63 along the corresponding edges of the base 35 and secured to the side edges of said carriage are gear racks 64 that mesh with pinions 65 at opposite ends of a shaft 66 which extends longitudinally of the printing mechanism 12 through medially allocated bearing bosses 67 100 on the base 35. The purpose of this compound gearing 64, 65 is to prevent binding of the carriage 61, as it is moved forward and backward of the type bed frame 38 incident to which upstanding cam lugs 68 (Figs. IV-VII) adjacent opposite side edges of said carriage, cooperate with cam lugs 69 depending from the side arms 43 of the frame 38 and serve to swing the latter up and down, thereby, at one time to bring the printing edge 115 47 of the type member sections 45, 46 into and out of contact with the printing pad 60; and, at another time, into and out of printing contact with the stocking S stretched on the board 10, also as later on fully explained. 120 The carriage 61 supporting the ink pad 60 is held to the guideways 63 on the base 35 by keeper pieces 70, 71 secured by screws to the foot flanges 72, 73 of said base, as shown in Fig. III; while the carriage 61 receives its movement from the actuating arm 17 whereby the stocking board 10 is swung toward and away from the printing mechanism 12. The intervening connections include a hook member 75 which is pivoted to the actuating lever 130

17 at 76 and provided forwardly of a shoulder 77 with a prolongation 78 having sliding guidance in a laterally projecting ear 79 of the carriage 61. The hook member 75 is adapted to engage a gravity dog 80 which is swingable about a stud 81 let into the contiguous side of the carriage 61. Outward movement of the carriage 61, i. e. toward the left in Fig. IV, ceases when the dog 80 falls away from the hook member 75, as shown in Fig. V, incident to dropping of its cam lug 82 off the end of the flange 72 of the base 35. Inward movement of the carriage 61 is, on the other hand, limited by stop abutments 83 upward from the top of the base 35, all as shown in Figs. I, II, IV and V.

The manner of using the device is as follows: With the parts positioned as in Fig. II, the operative stretches the stocking S over the board 10, and then presses against the actuating lever 17 with the knee. Immediately upon initiation of the inward swinging of the board 10 attendant upon this action, the hook member 75, through engagement of its shoulder 77 with the guide lug 79 on the carriage 61, causes said carriage to follow the movement of the actuating lever 17. Incidentally, the marking type sections 45, 46 and the number disk 52 are lifted from contact with the ink pad 60 as a consequence of raising of the type frame 38 through cooperation of the cam rises 68 on the carriage 61 and the depending cam lugs 69 on the frame arms 43, as shown in Fig. VI. The stocking board 10 is eventually arrested in the position of Figs. I and VI by the stop finger 23, in which position it is maintained by action of the coupling spring 21 between it and the actuating lever 17. The inward movement of the carriage 61 continues however as further pressure is brought to bear upon the actuating lever 17 in opposition to the torsion spring 20 until said carriage comes to rest against the stop abutments 83 of the base housing 35. Just as the carriage 61 reaches the abutments 83, the cam lugs 68 thereon are advanced beneath the depending cam projections 69 of the arms 43 of the printing frame 38. As a consequence of the descent of the printing frame 38 under these conditions, the printing or impress edges 47 of the type sections 45, 46 imprint the line mark L (Fig. II) upon the arrested stocking S on the board 10, the proper size number being at the same time imprinted on said stocking by the disk 52. After such printing of the stocking S, the pressure on the actuating lever 17 is gradually relaxed; and the ensuing retraction of said lever is attended initially by lifting of the printing frame 38 and raising of the type section 45, 46 from the stocking S as a consequence of the outward or reverse movement of the carriage 61 under pull of the dog 80 by the hook member 75. Upon accomplishment of the immediately fore-

going sequence of operations, the board 10 follows the movement of the actuating lever 17 until arrested in the normal retracted position of Fig. II by the stop finger 22. Also during the rearward movement of the actuating lever 17 the dog 80 finally drops away from the hook member 75, and this occurs just at the moment the lugs 68 clear the depending clamp projections 69 on the printing frame 38 as in Fig. V whereby the edges 47 of the marking type sections 45, 46 and the number disk 52 are brought into contact with the pad 60 to receive ink in readiness for the next operation. By proper adjustment of the stop 22 the normal or rest position of the board 10 may be so determined as to align properly with the sewing and cutting instrumentalities of the machine 14. Under these conditions, the stocking S may be fed directly to the sewing and cutting instrumentalities of the machine 14 as it is withdrawn from the board 10.

While my invention is particularly useful in connection with the manufacture of stockings such as disclosed in the patent hereinbefore referred to, I do not wish to be limited to such use alone since the device is capable of adaptation to marking stockings or knitted articles of other kinds. The number disk 52 may obviously be allocated otherwise on the printing frame 38 than herein described. For example, it may be so positioned as to print the size numbers on the toe of the stocking S if this should be more desirable. Furthermore, other type devices may be employed with, or in lieu of either or both the line type 45, 46 and the number disk 52, to print ornamental designs, trade marks or other identification marks upon the stockings.

Having thus described my invention, I claim:

1. In apparatus for printing knit or woven articles such as hosiery, printing mechanism including a pivotal type member; a support for the articles movable toward and away from the printing mechanism; and means whereby, as the support is presented to the printing mechanism, the type member is actuated by said movable support to apply an imprint upon the supported article.

2. In apparatus for printing knit or woven articles such as hosiery, printing mechanism including a vertically movable type member; a support for the articles swingable in a horizontal plane toward and away from the printing mechanism; and means whereby, as the support is presented to the printing mechanism, the type member is actuated by said swingable support to apply an imprint upon the supported article.

3. In apparatus for printing knit or woven articles such as hosiery, printing mechanism including a vertically movable type member; a support for the articles swingable

in a horizontal plane about a pivot axis at one end toward and away from the printing mechanism; and means whereby, as the support is presented to the printing mechanism, 5 the type member is actuated to apply an imprint upon the article.

4. In apparatus for printing knit or woven articles such as hosiery, printing mechanism including a rockable type member and 10 an ink pad; a support for the articles swingable toward and away from the printing mechanism; and means whereby, as the support is presented to said printing mechanism, the type member is downwardly rocked by 15 said swingable support to apply an imprint upon the supported article, and whereby, as the support is withdrawn from said printing mechanism, the type member is moved into contact with the ink pad in readiness 20 for the next printing operation.

5. In apparatus for printing knit or woven articles such as hosiery, printing mechanism including a vertically movable type member and an ink pad beneath said type 25 member; a support for the articles movable in a horizontal plane toward and away from the printing mechanism; and means whereby, as the support is presented to the printing mechanism, the type member is actuated to 30 apply an imprint upon the supported article, and whereby, as the support is withdrawn from the printing mechanism, the type member is permitted to descend into contact with the ink pad in readiness for the next printing 35 operation.

6. In apparatus for printing knit or woven articles such as hosiery, printing mechanism including a vertically rockable type member and an ink pad normally beneath 40 said printing member; a support for the articles swingable in a horizontal plane toward and away from the printing mechanism; and means whereby, as the support is presented to the printing mechanism, the ink 45 pad is moved out of the way and the type member downwardly rocked by said swingable support to apply an imprint upon the supported article.

7. In apparatus for printing knit or woven 50 articles such as hosiery, printing mechanism including a vertically movable type member, and an ink pad normally beneath said type member; a support for the articles movable in a horizontal plane toward and 55 away from the printing mechanism; and means whereby, as the support is presented to the printing mechanism, the ink pad is moved out of the way and the type member actuated to apply an imprint upon the supported article, and whereby, as the support is withdrawn, the ink pad is restored to 60 normal position beneath the type member, and said type member permitted to descend into contact with the ink pad in readiness for the 65 next printing operation.

8. In apparatus for printing tubular articles such as seamless knit hosiery, printing mechanism including a rockable type member; a flat profile mounting form to support the article, said form being swingable toward and away from the printing mechanism; and means whereby, as the form is presented to the printing mechanism, the type member aforesaid is rocked by the form to effect application of an imprint upon the 75 mounted article.

9. In printing apparatus for line marking seamless knit hosiery for the purposes of edge trimming; printing mechanism including a type member with an adjustable heel marking section; a flat profile mounting form for the stockings movable toward and away from the printing mechanism, said mounting form having a heel piece adjustable to correspond with the adjustment of the 80 heel printing section of the type member; and means whereby, as the form is presented to the printing mechanism, the aforesaid type member is actuated to apply a line imprint upon the mounted stocking.

10. In printing apparatus for line marking tubular knit articles such as seamless knit hosiery for the purposes of edge trimming; printing mechanism including a rockable member with a line type and a size marker; a flat profile mounting form for the article swingable horizontally toward and away from the printing mechanism; and means whereby, as the form is moved toward the printing mechanism, said mechanism is actuated by the swingable form to apply a line imprint and a size mark upon the mounted article.

11. In printing apparatus for line marking seamless knit hosiery for the purposes of edge trimming, printing mechanism including a line type member with an adjustable section for marking the heel of the stocking and a size marker with number type coordinated for simultaneous adjustment with the adjustable section of the line type member aforesaid; a flat profile mounting form for the stockings movable toward and away from the printing mechanism, said form having a heel piece adjustable to correspond with the adjustable section of the line type of the printing mechanism; and means whereby, as the form is presented to the printing mechanism, the latter is actuated to concurrently apply a line mark and the size imprint on the mounted stocking.

12. The combination with a trimming and sewing machine; of apparatus for line marking tubular articles such as seamless knit hosiery for the purposes of edge trimming and seaming, said apparatus including vertically rockable printing mechanism, and a flat profile mounting form for the article swingable horizontally toward and adapted to actuate the printing mechanism for pro- 125

duction of a line imprint upon such article, and subsequently away from said printing mechanism to a position facilitating the running of the marked edge of the article direct to the trimming and sewing elements of the machine aforesaid incident to stripping the article from the form.

5 In testimony whereof, I have hereunto signed my name at Philadelphia, Pennsylvania, this 6th day of June, 1930.
